UNITED STATES PATENT OFFICE

155,611

DESIGN FOR A PORTABLE HAND FIRE EXTINGUISHER

Theodore W. Johnson and Harley G. Hastert,
Marinette, Wis., assignors to Ansul Chemical
Company, Marinette, Wis., a corporation of
Wisconsin

Application October 28, 1948, Serial No. 149,344

Term of patent 14 years

(Cl. D16—2)

To all whom it may concern:

Be it known that we, Theodore W. Johnson and Harley G. Hastert, citizens of the United States, residing at Marinette, in the county of Marinette and State of Wisconsin, have invented a new, original, and ornamental Design for a Portable Hand Fire Extinguisher, of which the following is a specification, reference being had to the accompanying drawing, forming a part thereof.

Figure 1 is a front elevational view of the portable hand fire extinguisher showing our new design.

Figure 2 is a side elevational view of the fire extinguisher.

Figure 3 is a rear elevational view of the fire extinguisher, and

Figure 4 is a top plan view of the fire extinguisher taken on line 4—4 of Figure 3.

We claim:

The ornamental design for a portable hand fire extinguisher, as shown.

THEODORE W. JOHNSON.
HARLEY G. HASTERT.
